UNITED STATES PATENT OFFICE.

LANSING ONDERDONK, OF NEW YORK, N. Y., ASSIGNOR TO UNION SPECIAL MACHINE CO., OF CHICAGO, ILLINOIS, A CORPORATION OF ILLINOIS.

SPREADER OR LOOP-RETAINER FOR SEWING-MACHINES.

1,087,817.

Specification of Letters Patent.

Patented Feb. 17, 1914.

Application filed January 4, 1908. Serial No. 409,288.

To all whom it may concern:

Be it known that I, LANSING ONDERDONK, a citizen of the United States, residing at New York city, in the county of New York, 5 State of New York, have invented certain new and useful Improvements in Spreaders or Loop-Retainers for Sewing-Machines, of which the following is a description, reference being had to the accompanying drawing and to the letters and figures of reference marked thereon.

My invention relates to spreaders or loop retainers for sewing machines, and more especially to a spreader or loop retainer 15 adapted for use in connection with a hem stitch sewing machine, such as shown and described in my application Serial No. 94,589, filed Feb. 18, 1902, patented June 28th, 1910, #962,973, although from certain 20 aspects my invention is capable of use in connection with other types of machines.

In machines for making hem stitches, it is desirable at certain intervals to make two or more stitches without the feed operating 25 to advance the fabric. In machines of this character where the second stitch is made without the feed movement, it is often difficult to properly position the looper thread so that the needle will enter between that 30 portion of the looper thread running from the eye of the looper to the previous stitch and the looper body as ordinarily the feed of the material carries the looper thread back and spreads the looper thread loop for 35 the entrance of the needle.

The object of my invention is to provide a spreader or loop retainer which shall co-operate with the looper to hold the needle loop well back on the looper and the looper 40 thread at one side of the looper body so that the needle may properly enter between the looper thread and the body of the looper.

My invention consists in the parts, improvements and arrangements hereinafter 45 shown, described and set forth in the claims.

In the drawings which show by way of illustration one embodiment of my invention: Figure 1 is a front elevation of a sewing machine having my improved 50 spreader operating mechanism applied thereto. Fig. 2 is a detail showing the spreader operating and looper operating

mechanism in top plan view. Fig. 3 is a detail view showing the spreader support and the spreader mounted thereon. Fig. 4 55 is a detail view in top plan, showing the inclined eccentric and its connection to the spreader support. Fig. 5 is a sectional view through the inclined eccentric showing the connection of the eccentric strap to the 60 spreader support. Fig. 6 is a detail showing the main shaft with the inclined eccentric thereon, the eccentric strap being removed. Fig. 7 is a detail view showing the looper support and spreader support in side elevation. Fig. 8 is a detail view showing the 65 loopers and the spreaders with the loopers in their extreme rearward position. Fig. 9 is a similar view with the loopers in their extreme forward position. Fig. 10 is a 70 similar view showing the loopers having been given their lateral movement and the spreaders also moved laterally to engage the looper thread loop and to hold the same 75 away from the looper body for the entrance of the needle.

In the present illustrated embodiment of my invention, the bed plate 1 is provided with the usual work support 2, and the overhanging arm 3 to which is pivoted a needle 80 lever 4, operated from the main shaft 5 by a link 6 in the usual manner. The needle bar 7 is mounted to reciprocate in a gate 8 which by means of a link 9 may be oscillated from a suitable cam. A second needle 85 bar is preferably employed which is located in rear of the needle bar 7, and mounted to reciprocate in the gate 10 which is oscillated by a link 11 from a suitable cam. Suitable piercers are employed which operate to 90 penetrate the fabric in advance of the stitching, and assist the stitching mechanism in making the open spaces, or what is known as hem stitching. The feeding mechanism is preferably of the type shown in my patent 95 above referred to and said feeding mechanism operates to advance the fabric at every third stitch.

The needle mechanism will not need further description herein, as the same forms no 100 part of the present invention.

Co-operating with the needles carried by the needle bars are two thread carrying loopers 12 and 13. Said loopers are mount-

ed in a looper carrier 14 which is pivoted at 15 to the usual looper support 16. The loopers are oscillated by the usual link 20, which receives movement from the needle lever through a rock lever 20^a and a link 20^b, which give to the loopers a differential movement. The looper support is pivoted on two hollow shaft bearings, one of which is shown in dotted lines at 16', Fig. 7, and the other is shown at 16'' in said figure. The short hollow shaft bearing 16' is mounted in the bracket 18 and extends into the looper carrier 16. The hollow shaft bearing 16'' extends through the bracket 19 and into the bracket 19'. The looper carrier 16 is firmly secured to said shaft bearings in any suitable manner. The yoke 21 is also secured to said shaft between the bearings 19 and 19' and engages a suitable eccentric on the main shaft 5. As the main shaft 5 rotates, the yoke 21 will be oscillated and this in turn will oscillate the hollow shaft bearing 16'' and the looper carrier 16 to give to the looper its lateral or needle avoiding movement. The rod 17 is mounted within the hollow shafts 16' and 16'', so as to oscillate freely therein and to move longitudinally therein. This rod 17 is provided with a spreader carrier 22 on which are mounted spreaders 24, 25 which coöperate respectively with the loopers 13 and 12. The supporting rod 17 is oscillated and is moved longitudinally in its bearings by means of an eccentric 26, secured to the main shaft 5. An eccentric strap 27, encircles said inclined eccentric and at its outer end is connected to a ball stud secured to a block 29 mounted on the rod 17 and held thereon by a suitable screw 30. Said stud 28 projects downwardly from the block 29 and it will be seen therefore, that the connection between the eccentric strap and the spreader support is at a point below the axis of said support. As the main shaft 5 rotates, the eccentric strap 27 will be vibrated back and forth by the inclined eccentric and said vibrations of the eccentric strap 27 will give to the spreader supporting rod 17, a longitudinal movement and in turn to the spreaders, a back and forth movement. Also as the main shaft rotates the eccentric strap will be moved longitudinally, due to the fact that the member 26 is set eccentrically to the shaft 5. This longitudinal movement of the eccentric strap will give to the supporting rod 17 an oscillation and in turn a lateral movement to the spreaders relative to the loopers. The operation of my device is as follows:—When the loopers are at the extreme rear end of their stroke, the spreaders are also at the extreme rear of their stroke. As the loopers move forward into the needle

loop, the spreaders also move forward until the points thereof are moved a short distance across the line of feed. Said spreaders are also on the front side of the needles and loopers as viewed by the operator and therefore, as the loopers are moved laterally to give thereto the needle avoiding movement, the spreaders are brought into contact with the looper thread running from the eye of the loopers to the previous concatenation of the threads. The spreaders are at this time also given a slight lateral movement and the looper thread is crowded back so that the needle will with certainty pass between the looper thread and the looper body. The needles as they descend, enter between the spreader fingers and the loopers. As the spreaders move across the upper face of the loopers, the needle loop on the loopers will also be crowded back on said loopers and properly held away from the needles as they descend, so that the needles will with certainty enter between the usual triangle formed by the looper thread, the looper body and the needle loop.

The loop spreader described above is of the special advantage when used in connection with a hem stitch machine, wherein there are idle movements for the reason that the feed of the fabric is usually depended upon to position the looper thread and the needle loop for the proper entrance of the needle. My improved spreader secures the same function as the feeding of the fabric and therefore, properly positions the looper thread and needle loop when there is no feed movement taking place. I do not however, claim broadly herein the spreader operating to position the looper thread and the needle loop when no movements take place, as the broad invention is shown described and claimed in my co-pending application above referred to.

Having thus particularly described my invention, what I claim as new and desire to secure by Letters Patent is:—

1. The combination with a needle, a looper, means for operating said needle and looper, of a spreader and an inclined eccentric for giving to said spreader a forward and back and a lateral movement, whereby the looper thread and needle loop are properly positioned for the entrance of the needle.
2. The combination with a needle, a looper and means for operating the same, of a spreader and means for operating said spreader including an inclined eccentric and connections whereby said spreader is moved forward as the looper is moved forward, and said spreader is moved laterally as the looper is moved laterally, to engage the looper thread and properly position the

same for the entrance of the needle between said looper thread and the looper body.

3. The combination with a needle, a looper, a looper support and means for operating the same, of a spreader pivoted on the same axis as said looper support, and means for giving said spreader a lateral movement relative to said looper, whereby said spreader is moved into engagement with the looper thread, to position the same for the entrance of the needle between said looper thread and looper, said spreader being positioned so as to move across the path of the needle whereby the needle loop is engaged and crowded back on said looper.

4. The combination of a needle, a looper, a looper support, a spreader, a spreader support on which said looper support is pivotally mounted, a spreader carried by said spreader support, and means for moving said spreader and oscillating the same laterally relative to the looper, whereby the spreader is brought into engagement with the looper thread for properly positioning

25 the same for the entrance of the needle between said thread and the looper body, said spreader being so positioned as to move across the path of the needle, whereby the needle loop is engaged and crowded back on said looper.

5. The combination of a needle, a looper, a looper support, means for operating the same and a spreader pivoted upon the same axis as said looper support and an inclined eccentric for operating said spreader.

6. The combination with a needle, a looper, a looper support, means for operating the same, of a spreader, a spreader support on which said looper support is pivotally mounted and an inclined eccentric for moving said spreader support longitudinally and oscillating the same.

7. The combination with a needle, a looper, a looper support, a looper carrier pivoted to said looper support, of a spreader, a spreader support on which said looper support is pivoted, said spreader facing in the opposite direction from said looper, and means for moving said spreader bodily forward and back and for oscillating the same.

8. The combination with a needle, a looper, a looper support, a looper carrier pivoted to said looper support, of a spreader, a spreader support on which said looper support is pivoted, said spreader facing in the opposite direction from said looper, and an inclined eccentric for giving said spreader a forward and backward movement and for oscillating the same.

9. A spreader mechanism including in combination a looper, and means for operating the same, a spreader support, a spreader carried thereby, a main shaft and an in-

clined eccentric mounted on said main shaft 65 for moving said spreader support longitudinally and for oscillating the same.

10. A spreader mechanism including in combination, a spreader, a spreader support, a main shaft, an inclined eccentric thereon, 70 an eccentric strap co-operating with said eccentric, a ball stud carried by said spreader support and projecting downward therefrom to which said eccentric strap is connected.

11. In a sewing machine, the combination 75 of a needle, a looper, means for operating the needle and looper, a spreading device extending in the same general direction as the looper, and means for moving the spreading device across the longitudinal 80 axis of said looper, said spreading device being so shaped and disposed as to engage the loop of needle thread on the looper, whereby said needle loop is crowded back on the looper, and said spreading device being so 85 shaped and disposed as to engage the looper thread for holding the same away from the body of the looper.

12. In a sewing machine, the combination 90 of a needle, a looper, means for operating the needle and looper, a loop-spreading device having a curved end, means for moving said loop-spreading device across the upper face of the looper, and the outer curved face thereof into engagement with the needle 95 loop on the looper, whereby said needle loop is crowded back on the looper, said loop spreader being so disposed relative to the looper that said spreading device engages the looper thread and separates the same 100 from the body of the looper, and the curved end of the spreading device forms a space for the needle to enter between the spreading device and the body of the looper.

13. In a sewing machine, the combination 105 of a needle, a looper, means for operating the needle and looper, a spreading device extending in the same general direction as the looper, means for moving the spreading device across the longitudinal axis of said 110 looper, said spreading device being so shaped and disposed as to engage the loop of needle thread on the looper, whereby said needle loop is crowded back on the looper, and said spreading device being so shaped and disposed as to engage the looper thread for holding the same away from the body of the looper, and means for operating the looper at a variable speed relative to said loop-spreading device.

14. The combination of a needle, a looper, means for operating said needle and looper, a spreader, a single actuating element and devices for imparting to said spreader a forward and backward and lateral movement 125 from said actuating element, said spreader being so disposed relative to the looper as to engage both the looper thread and the

needle loop on the looper, whereby the looper thread is moved away from the body of the looper and the needle thread loop is crowded back on to the looper and the looper thread and needle thread loop properly positioned for the needle to pass between the same and the body of the looper.

15. The combination with a needle, a looper, means for operating said needle and looper, of a spreader, and an inclined eccentric

for giving to said spreader a forward and back and a lateral movement, whereby the needle loop is properly positioned for the entrance of the needle.

In testimony whereof I affix my signature, 15
in presence of two witnesses.
